United States Patent Office

Des. 198,178
Patented May 12, 1964

198,178

CLOCK

John T. Mains, 229 Kimbler Ave., Syracuse, N.Y.

Filed Dec. 17, 1963, Ser. No. 77,872

Term of patent 14 years

(Cl. D42—7)

FIG. 1.

FIG. 2.

FIG. 3.

FIGURE 1 is a front elevational view of a clock showing my new design;

FIGURE 2 is a top plan view thereof; and

FIGURE 3 is a side elevational view thereof.

This application is a continuation in part of my earlier filed application #D-69,583 filed April 4, 1962, and now abandoned.

I claim:

The ornamental design for a clock, as shown and described.
